UNITED STATES PATENT OFFICE.

CHARLES H. KENDRICK, OF WINCHESTER, NEW HAMPSHIRE.

COAGULANT-FEEDER.

SPECIFICATION forming part of Letters Patent No. 417,046, dated December 10, 1889.

Application filed May 9, 1889. Serial No. 310,136. (No model.)

To all whom it may concern:

Be it known that I, CHARLES H. KENDRICK, a citizen of the United States, residing at Winchester, Cheshire county, New Hampshire, have invented certain new and useful Improvements in Coagulant or Reagent Feeders, fully described and represented in the following specification and the accompanying drawings, forming a part of the same.

This invention is designed to furnish an automatic device which may be actuated by the variations of pressure arising in the cylinder of any supply-pump which may be used to furnish the fluid to such filter. Where a pump has been used to supply the water to a filter, a coagulant-feeder has been constructed with a plunger of suitable proportions connected directly with the reciprocating cross-head or other moving part of such pump, the volume of coagulant delivered by each stroke of the pump being thus proportioned to the volume of the fluid passed through the filter. By such a construction the proportion of coagulant to each gallon of water passed through the filter could not readily be varied; and the object of my invention is to furnish a construction that may be actuated by the intermittent variation of pressure in the pump-cylinder and adapted, at the pleasure of the operator, to deliver a greater or less amount of coagulant at each reciprocation of the supply-pump.

My device consists in a motor-piston having one side exposed to the variable pressure existing in the cylinder of the supply-pump and connected with a plunger adapted to draw the coagulant from a suitable receptacle and force it into the filter, and means being provided to regulate the stroke of the motor-piston, and to thus vary the volume of coagulant delivered by the plunger at each stroke of the supply-pump. The means for regulating the stroke of the motor-piston is easily furnished by inserting an adjustable stop through the head of the motor cylinder or casing, with which the motor-piston would come in contact at one end of its stroke, and the stroke may thus be made longer or shorter at pleasure.

The invention will be understood by reference to the annexed drawings, in which—

Figure 1 is an elevation of a filter with a supply-pump and coagulant-feeder constructed according to my invention. Fig. 2 is a longitudinal section of the coagulant-feeder on its center line where hatched. Fig. 3 is an end view of the head provided with the adjustable stop and pressure-pipe, the cap upon the stuffing-box being removed. Fig. 4 is an end view of the opposite head with the coagulant-cylinder attached, and Fig. 5 an alternative construction in section like Fig. 2.

The apparatus is adapted to feed any kind of chemical reagent, whether intended to produce a precipitate in the water or not.

F is the filter; G, the bed of a steam-pump for supplying the same with water; H, the steam-cylinder of such pump; I, the water-cylinder; J, the piston-rod between the two cylinders; K, the suction-pipe of the pump, and L the pipe delivering the water to the filter.

Figs. 1 and 2 show the coagulant-feeder constructed with cylinders and pistons movable therein, while Fig. 5 shows a coagulant-feeder constructed with flexible diaphragms.

The cylinder a of the coagulant-feeder is connected by the pipe e with the interior of the water-cylinder I, and the coagulant-pipe b⁴ from the cylinder b is connected with a coagulant-tank M and with the filter-pipe L.

In Fig. 2, a is the motor-cylinder; a', one of its heads, having the coagulant-cylinder b attached. c is the motor-piston fitted to cylinder a, and d a coagulant-pump plunger attached to the piston c by a stem d'. a² is a head at the opposite end of the motor-cylinder, provided at its center with a threaded nozzle h, having cap i to form a stuffing-box. A screw j, having shank j' extended through the stuffing-box, is inserted in the nozzle and provided at its inner end with the stop f, adapted to arrest the stroke of the piston c. The pressure-pipe e is shown connected by a passage e' in the head a² with one end of the cylinder a, and the opposite end of the cylinder is shown connected with the atmosphere by a pipe g, provided at its upper end with a cup g', having a screw-cover g².

Branches m and m' connect the coagulant-cylinder, respectively, with a tank of precipitant and with the filter, and check-valves m² are shown inserted in such branch pipes to

permit the movement of the coagulant through the pipe *m* to the cylinder *b* and from the same to the filter.

The object of the stop *f* is to adjust the 5 stroke of the piston *c* to deliver the desired volume of coagulant from the cylinder *b*.

The operation of the apparatus is as follows: The alternate pressure and vacuum existing in the cylinder *I* produces an intermittent pressure upon the piston *c*, the pressure of the atmosphere operating through the pipe *g* when a vacuum is induced in the cylinder *a* to force the piston toward the stop *f*, and to thus draw the plunger *d* backward 15 from the pipe *b*⁴. When the pressure is renewed in the cylinder *a*, the motor-piston *c* forces the plunger *d* outward and expels the contents of the coagulant-cylinder. The movement of the plunger *d* thus operates to 20 draw the coagulant alternately from the tank *M* and forces it through pipe *m'* into the pipe *L* to operate upon the water before the same is filtered. The cover *g*² upon the cup *g'*, attached to the air-pipe *g*, is provided with a 25 hole *g*³ to admit the atmospheric pressure. With such construction the cup answers not only to prevent the entrance of dirt or grit to the cylinder *a* when the air operates through the cup, but it permits the introduction of 30 oil or other lubricant within the cylinders *a* and *b* by placing a suitable supply of such liquid in the cup, the level of the liquid rising and falling in the cup as the motor-piston moves back and forth.

35 The plunger *d* requires to be of less diameter than the piston *c*, as the pressure in the pipe *L* is obviously the same as in cylinder *I*, and the difference of area between the piston *c* and plunger *d* may therefore be made suitable 40 to overcome the friction of such pistons and of the liquid in the pipes. A construction operating with less friction is shown in Fig. 5, where two diaphragms *s* and *s'* are shown secured movably at their margins in adjacent casings *t* and *t'*, which are open to one another upon their adjacent sides. The two diaphragms are connected by a rod *s*², so that the movements of the larger diaphragm operate upon the smaller. One side of the casing *t* is provided with the pipe *e* to connect it with the cylinder *I*, and the opposite side of the chamber *t'* is connected with the pipe *b*⁴ to admit the coagulant, as already described. A stop *f* is also shown applied to the outer side of the diaphragm *s*, and its movement 55 in the opposite direction is arrested by contact with the casing *t*. A pipe *t*² admits air between the diaphragms to operate like the pipe *g* in Fig. 2.

60 It is obvious that the area of the larger

diaphragm permits it to operate effectively upon the smaller diaphragm to propel the coagulant against the pressure in the pipe *L*, as desired, and the diaphragms may thus, for the purposes of my invention, be regarded as 65 pistons, vibrated, one of them, by the variations of pressure in the pump-cylinder *I* and the other vibrated by its connection therewith. The diaphragm *s* operates as the motor-piston, and the diaphragm *s'* operates as 70 the pump-plunger to propel the coagulant in precisely the same manner as the plunger *d* in Fig. 2.

The term motor piston and plunger used in the claims is intended to cover either 75 of these constructions, provided the motor-piston be of larger area than the coagulant-plunger, so as to deliver the coagulant under a pressure equal to that which operates the motor-piston. The cylinder *a* may also be regarded as a casing to confine the pressure upon the piston *c* in the same manner as the casing *t* confines the pressure upon the diaphragm *s*, and the term "casing" used herein thus includes either construction. 80

Having thus set forth my invention, what I claim herein is—

1. The combination, with a filter and a supply-pump controlling the passage of the fluid through the filter and having a fluid-cylinder 90 in which the pressure is intermittently varied, of a motor-piston in communication with the said pump-cylinder, a coagulant-plunger actuated by such motor-piston, a receptacle of coagulant or chemical reagent, and pipes 95 and valves connecting the receptacle with the filter and with the pump-plunger, the whole arranged and operated to deliver a charge of coagulant into the filter at each reciprocation of its supply-pump, substantially as set forth. 100

2. In a coagulant feeder having a motor-piston actuated by an intermittent variation of pressure upon one side thereof, the combination, with the casings *t* and *t'*, connected together as described, of the diaphragms *s* 105 and *s'*, of different diameters, connected together, the pipe *e*, for connecting the casing *t* to the pump-cylinder *I*, the pipe *b*⁴, for connecting the smaller diaphragm with the coagulant-receptacle and with the filter, and the stop *f*, to regulate the movements of the diaphragms, substantially as herein set forth. 110

In testimony whereof I have hereunto set my hand in the presence of two subscribing witnesses.

CHARLES H. KENDRICK.
